Samson Wolff

UNITED STATES PATENT OFFICE.

SAMSON WOLFF, OF VICKSBURG, MISSISSIPPI.

IMPROVEMENT IN COTTON AND HAY PRESSES.

Specification forming part of Letters Patent No. 24,256, dated May 31, 1859.

To all whom it may concern:

Be it known that I, SAMSON WOLFF, of Vicksburg, in the county of Warren and State of Mississippi, have invented certain new and useful Improvements in Cotton and Hay Presses; and I do hereby declare that the following is a full, clear, and exact description of the construction and operation of the same, reference being had to the accompanying drawings, in which—

Figure 1 represents a front view of said press. Fig. 2 represents a vertical cross-section through the same.

To enable others skilled in the art to make and use my invention, I will proceed to describe its construction and operation.

A represents the frame of the press.

B represents the side of the press-box, and C the follower.

D is a plank, which is secured to the lower side of the follower.

E is a rack, which is secured to the plank D in an oblique position, as shown in Fig. 1.

F represents the pinion which actuates the rack E when the machine is in operation. The pinion F is made of a spiral shape—that is, the cogs are formed thereon in a spiral order—the distance of each cog from the center of said pinion being larger or smaller, respectively, than the succeeding cogs, while at the same time the cogs in the longitudinal direction advance in a screw-line, thereby giving the pinion a conical spiral form. It is evident that if said pinion shall be in constant gear with the rack E said rack must have an oblique position, as represented in Fig. 1, and also that it must be tapering, as represented in Fig. 2, for as the plank D is guided in its motion by the guides a, and cannot move sideways, the teeth on a larger or smaller diameter

of the pinion could not be in contact with the teeth of said rack if the thickness of the rack would not increase at the same rate as the diameter of the spiral pinion decreases by its revolution. By this simple arrangement I am enabled to impart to the follower C a quick motion at the commencement of the pressing operation, while as the pressing progresses the power of the press is increased, while the motion of the follower becomes slower. This is the principle on which all good presses ought to be constructed, as by it a great deal of time is saved, and I obtain this object by the simple and effectual contrivance above described.

b represents a rack, (shown in red,) which may be secured to the side of the plank C. The pawls d operate on said rack, and thus prevent the follower from receding by the expansion of the cotton when the latter has been subjected to pressure.

In the operation of the machine the cotton is filled into the box B, and by turning the crank G, the pinion F operates upon the rack E, and as the pressure increases the velocity of the rack diminishes.

Having thus fully described the nature of my invention, I would state that I do not claim the combination of a cogged cam-wheel or geared eccentric with an inclined rack; but

What I do claim, and desire to secure by Letters Patent, is—

The combination of a conical spiral wheel or pinion with an inclined rack, when the latter is set oblique to the axis of the pinion, substantially in the manner and for the purpose herein described.

SAMSON WOLFF.
